EUGENE A. FORD, OF WEST NEWTON, MASSACHUSETTS, AND FREDERICK A. STORY, OF ENDICOTT, NEW YORK, ASSIGNEES TO THE TABULATING MACHINE COMPANY, OF ENDICOTT, NEW YORK, A CORPORATION OF NEW JERSEY

COUNTER FOR TABULATING MACHINES

Application filed April 17, 1923. Serial No. 632,611.

The present invention is directed to the provision of an improved accumulator for use in tabulating machines.

Broadly, the present invention is directed to the provision of an accumulator having a plurality of sets of accumulator elements such as counter wheels, in which common actuators are provided for concurrently controlling the moving of wheels or other elements in both accumulators and in which the movement of the common actuators is controlled directly from the record cards.

Heretofore in tabulators of the Hollerith type it has been the practice to utilize a plurality of counters electrically plugged together when it was desired to take sub and grand totals. While satisfactory results may be thus secured, the counter capacity of a machine is in a measure limited. In the present invention, the counter or accumulator is made double with two sets of wheels. Both sets are controlled by a common set of counter magnets. A single set of actuators is provided for both sets of wheels. The actuators are themselves directly controlled by the counter magnets.

Further objects of the present invention reside in an improved accumulator construction which will permit the resetting of one accumulator without disturbing the resetting of the other accumulator.

Other objects of the present invention reside in the provision of certain interlocking devices to prevent errors in the accumulation upon resetting operations.

Further objects of the present invention will be hereafter described in the accompanying specification and claim and shown in the drawings which by way of illustration portray a preferred embodiment of the invention.

In the drawings,

Fig. 1 is a sectional view of my improved accumulator. The section is taken on line 1-1 of Fig. 5.

Fig. 2 is a different sectional view taken on line 2-2 of Fig. 5.

Fig. 3 is an end view of the counter unit looking from the right in Fig. 5. This view

also shows certain details of the drive for the resetting mechanism.

Fig. 4 is a detail sectional view with certain parts omitted. The section is taken on line 4-4 of Fig. 5.

Fig. 5 is a front view of the device with certain parts broken away to show the interior construction.

Fig. 6 is a detail view of the reset throwout clutch for the upper counter or accumulator. This view is taken substantially on lines 6-6 of Fig. 1.

Fig. 7 is a detail view taken on line 7-7 of Fig. 1 of the clutch devices and shows their control by the magnets.

Figs. 8 to 14 are detail views of the counter wheels, the sections being taken on correspondingly numbered lines in the different views.

Fig. 15 is a circuit diagram and shows diagrammatically the card feed devices.

Before describing the apparatus, the circuit diagram will be briefly described. 20 designates the stack of cards from which a picker device 21 takes the cards one at a time 75 and advances each card to rolls 22, which feed the cards past the brushes and contact blocks 22a. Gearing 23 drives the rolls and picker and rotates counter drive shaft 24. These gears are rotated by the tabulating motor T. M. 25 are the counter magnets and 26 the counter relays. The latter are, through the plug board 27 and suitable leads, connected to the contact blocks 22a. 30 is the emergency stop key and 31 the start key. 32 and 32a are the main motor and motor-control relays. 33 is a relay for supplying current to the counter relays and counter magnets after the card lever contacts 28 have been closed. Cams 34, 35 and 36 are those commonly used in tabulating machines to control the circuits thereof.

Referring to the counter mechanism, 24 is the main tabulator drive shaft carrying suitable gears 40 shown in dotted lines in Fig. 3 meshing with a gear 41 on each counter. This gear is fixed to a shaft 42 which also has fixed to it a gear 43 meshing with a gear 44 fixed on shaft 45 (see Figs. 2 and 4). The shaft 45 is the main clutch shaft of this coun-

ter. Splined to shaft 45 are a number of clutch elements 48, (Fig. 7), which are adapted to be engaged with clutch elements fast to gears 49, which gears are rotatable upon the shaft 45. The selective engagement of the clutches 48 is effected by the energization of the counter magnets 25. The energization of any magnet attracts its armature 50 rocking the same and thereby rocking pivoted member 51 to engage the clutch. Disengagement of the clutches is effected by the spring impelled pivoted members 52. The parts heretofore described are of the usual and well known form and function as in the well known Hollerith counter.

In place of having a single set of counter wheels which are turned by the gears 49, the present invention contemplates a dual set of wheels, and for this purpose there are provided two counter wheel shafts 46 and 47. Rotatably disposed upon these shafts are gears 53 and 54 which mesh with the common intermediate clutch driven gears 49 (see Figs. 1 and 2).

On each of the shafts 46 and 47 there is provided a set of counter numeral wheels 55. Inasmuch as it may be desired to reset one of the sets of counter wheels without resetting the other set provision must be made for permitting the turning of one set of wheels to zero without imparting rotational movement to the wheels of the other set through the common intermediate driving gears 49. For this purpose certain ratchet and pawl driving means are provided intermediate the counter wheels and their driving gears 53-54.

Referring now to Figs 8 to 14, inclusive, each gear 53 and 54 is rotatably mounted upon the shafts 46-47. The right hand or units counter wheel of the upper set is provided with an integral disc 56, as shown in Figs. 11 and 12, and upon the lower wheel set this integral disc is replaced with a disc 57 having a serrated periphery and securely riveted to gear 53. (See Figs. 13 and 14.)

Upon other of the wheels of the upper set the integral discs just mentioned are omitted. (See Fig. 10.) Upon the wheels of the lower set except for the one at the extreme right, disc 57 is omitted and replaced by a series of pins 58 riveted directly into the gears 53. (See Figs. 8 and 9.) Cooperating with the serrated disc 57 and the pins 58 of the lower set of wheels are fingers of a transversely extending spring pressed bail 59 (see Figs. 1 and 5). This arrangement serves as an overthrow preventor or lock. Suitably fixed to each gear 53 and 54 is a ratchet 60 (Figs. 11, 12, 13 and 14). Cooperating with this ratchet are pawls 61 which are pivotally carried upon a disc 61a, which is suitably fixed to each wheel 55 and are spring pressed into engagement with the ratchet 60 by springs 62. Upon the counterclockwise rotation of the

driving gears 53 or 54 the ratchets 60 will, through the pawls 61, serve to carry the counter wheels 55 forward.

Also fixed to each counter wheel 55 is a transfer ratchet 63 having a single high tooth 64. This transfer ratchet carries a pawl 65 which is spring pressed into contact with the counter supporting shaft and is adapted to engage a reset notch 65a on that shaft when the shaft is turned to reset the counter wheels to zero. During such resetting movement the counter wheels may turn counterclockwise without causing any rotation of their driving gears by reason of the ratchet and pawl connections 60-61. This construction permits the resetting of the lower set of counter wheels without affecting the setting which may then be on the wheels of the other set. During adding operations it will be understood that the adding in of amounts upon both the upper and lower sets of counter wheels takes place concurrently.

To effect the resetting, provision is made for turning both shafts 46 and 47 or for disabling the connection to one shaft. Referring now to Fig. 3, a gear 66 is provided mounted upon a reset shaft (not shown) and turned by a crank or by an electric motor in the usual manner. Rotation of this gear effects rotation of gears 67, 68 and 69. The gear 67 is directly connected to shaft 46 and upon being rotated resets the lower counter wheels to zero. Gear 69 is not fixed directly to the shaft 47, but is adapted to be clutched to said shaft by a clutch 70 (Fig. 6). This clutch may be engaged or disengaged by moving a handle 71 (Fig. 1). The handle is provided with a cam member 72 which is adapted to displace a pivoted lever 73 (Fig. 6) and engage the clutch. A suitable spring 74 retracts the pivoted lever upon the disengagement of the handle. To properly align the shafts at the end of a resetting operation a zero lock lever 75 is provided which is spring pressed to engage a V-shaped notch in a disc 76 carried by shaft 46 (see Fig. 1). The instrumentalities just described permit the joint resetting of both the upper and lower counter wheels or only the resetting of the lower set.

The parts generally marked 77 in Fig. 1 constitute the transfer mechanism for the lower counter wheels. These transfer devices may be of any desired form, (for example, those shown in Hollerith Patent No. 974,272).

These transfer devices are tripped by the high teeth of the transfer ratchets upon the wheels and the relatching operation and completing of the transfer is effected by a transfer cam 78 upon transfer cam shaft 42.

The upper wheels are also provided with transfer devices 79-80, and these devices are adapted to be set up by means of a bail 80a and of a linkage 81 (see Fig. 2) extended to

a bell crank on rock shaft 82 having a follower cooperating with cam 83 on shaft 42 (see Fig. 2).

During resetting operations a pivoted member 85, Fig. 3, is rocked counterclockwise by a pin 86 on gear 66, so that the notch 87 of member 85 engages a pin 88 to rock a member 90 (Fig. 4) in a counterclockwise direction whereby the usual bail 91 is thrown into engagement with the transfer trip pawls of the lower set, thus preventing their being tripped upon the resetting operation. Concurrently, a lever 92 is elevated, which elevates brake members 93 (Fig. 2) into contact with the peripheries of the wheels, thereby preventing their spinning ahead of their pawl and ratchet devices and overtravelling. Concurrently the overthrow lock 59 is permitted to advance into the path of the cooperating pins 58 and notched disc 57.

While the upper wheels are being reset, an arm 94 connected to the lever 71 assumes a position to interfere with the movement of the bail 80a and thus prevent the pawls 79 being tripped during the resetting operation.

Just as the completion of the adding operation a cam 96 on shaft 42 (Fig. 4) operates the link 95 and lever 92 is elevated, the brake members 93 come in contact with the peripheries of the counter wheels 55 and thus prevent them from spinning ahead or overthrowing.

The shifting of the bar 91 under the action of cam 78 (Fig. 1) permits a cam projection of an arm 90 (see Fig. 4) of the cross bar to engage with a finger of the lock bar 59 to shift the latter to free the wheels during resetting and adding operations. The bar 91 as it is shifted to the right under control of cam 78 during adding operations permits the re-engagement of the lock bar with the wheels. During resetting operations when the bar 91 is shifted to the right under the action of member 85 (Fig. 3) to hold the transfer trip pawls the bar permits the overthrow lock to re-engage the adding wheels at the same time the friction brake engages the periphery of the adding wheels.

What we claim as our invention is:

50 An accumulator for accumulating amounts from perforated record cards, said accumulator comprising a double set of register wheels, a single set of actuators for said wheels for operating both sets in an additive direction to enter the same amount simultaneously, driving means for said actuators, a single set of magnets adapted to be controlled from perforations in record cards, means controlled by said magnets for effecting driving connection between said actuators and said driving means and similar releasable connecting mechanisms intermediate each set of registering wheels and the actuators to permit resetting of one set with

retention of the reading on the other set of wheels.

In testimony whereof we hereto affix our signatures.

EUGENE A. FORD. 70
FREDERICK A. STORY.
